MACHINE FOR HARVESTING BEETS AND LIKE TUBERS

Cornelis J. Steketee, 11 Korteweg, Driewegen,
Zevenbergen, Netherlands

Filed Sept. 27, 1960, Ser. No. 58,805

Claims priority, application Netherlands Oct. 12, 1959
4 Claims. (Cl. 171—58)

The invention relates to a machine for harvesting beets and like tubers, said machine being provided with at least one pair of mutually cooperating circular sets of rod-shaped lifting elements. Said lifting elements are arranged in such a manner that the summit of the acute angle enclosed by the elements in their lowermost position with the central longitudinal plane of the machine is directed forwards. Each rod-shaped lifting element of the one set is followed in the direction of rotation of the sets by a rod-shaped lifting element of the other set.

A machine of this kind is known in which both sets of rod-shaped lifting elements cooperating with each other are secured on a common rotating shaft extending transversely in horizontal direction. With said known machine the rod-shaped lifting elements approach the beet to be lifted out of the ground from above and it appeared that the lifting elements can hit the head of the beet and then damage same.

The invention has for its object to remove said drawback and to this end each circular set of lifting elements is secured to a separate shaft section and driving means being provided for rotating said shaft sections in the same sense, and the axes of said shaft sections enclosing an angle with each other of at least 140° and not exceeding 160° and having its summit directed upwards. With said position of the shaft sections the rod-shaped lifting elements are approaching the beet laterally so that they can not hit the head of the beet, whereas the lifting action of the rod-shaped elements is still maintained.

Preferably a grate is arranged between the sets of lifting elements, and a conveyor for receiving the beets and according to the invention the plane containing the axes of both shaft sections may enclose with a horizontal plane an angle of at least 60° and not exceeding 80° as viewed in the direction of travel of the machine. With said embodiment the beets receive an additional upwards directed component.

The invention will further be described with reference to the accompanying drawing showing an embodiment of the machine according to the invention.

In the drawing:

FIG. 1 is a diagrammatical side view of a part of both circular sets of lifting elements with a grate located behind said sets of lifting elements.

FIG. 2 is a plan view of the lifting elements and of the grate.

FIG. 3 is a front view of the machine on a smaller scale.

The shaft sections 4a and 4b each carry a disc 5 to which blade-like or foot-shaped lifting or striking elements 2 and 3 respectively are secured by means of radial arms 1. Each striking element has a toe portion 2a or 3a and a heel portion 2b or 3b. The shaft sections 4a and 4b enclosing with each other an angle having its summit di-

2

rected upwards. Said shaft sections 4a and 4b are supported in brackets 14a and 14b respectively and said brackets form part of a frame 13 and to each of said shaft sections a bevel gear 15a and 15b respectively is secured and said gears mesh with each other.

5 The gear 15b is driven by a conical pinion 16 secured to a driving shaft 6 in such a manner that the discs 5 are rotated in the same sense as indicated by the arrow b in FIG. 1.

10 Between the discs 5 and the conveyor 7 for taking up the beets and carrying same upwards a grate 8 is arranged, said grate being V-shaped and terminating in a nose 9 which is inclined downwards to a certain degree. The grate 8 is provided with arms 10 bent upwards and by means of said arms the grate is secured to a part 11 of the frame of the machine. The grate has three or more longitudinal bars 12 and the central bar of said bars is lying on a higher level than the outer bars.

15 The machine which is provided with ground wheels 17 is moved forwards on the ground above a row of beets 20 in the direction of the arrow a shown in FIG. 1 and the rod-shaped lifting elements 1 will alternately press on the one side and the other side against the beet so that it will be shaken and lifted out of the ground and thrown to the rear on the conveyor 7.

25 With the embodiment shown in the drawing the foot-shaped elements 2 and 3 respectively may be located approximately in the plane of the discs 5, but in their lowermost position the rod-shaped elements should enclose with the vertical longitudinal plane of the machine an acute angle having its summit directed forwards. The width of the elements 2 and 3 increase towards their end, or heel portions, contacting the beet in order to obtain a large pressure surface.

30 The shaft sections 4a and 4b of the discs 5 preferably are directed so as to have the plane containing their axes enclosing with a horizontal plane an angle of at least 65° and not exceeding 80° as viewed in the direction of the arrow a. With the described construction each striking element when in its lowermost, or beet striking, position has its toe inclined upwardly and outwardly and its heel substantially in or approaching the vertical central plane of the machine, and as a result the beets receive from the lifting elements a blow having an upwardly directed as well as a lateral component so that the beets are ultimately guided on to the grate 8.

What I claim is:

1. A machine for harvesting beets and like tubers comprising at least one rotatable member having two sets of 50 oppositely disposed foot-shaped, beet striking elements, the striking elements of one set being mounted in staggered relation with respect to the striking elements of the other set, each said striking element having a toe portion and a heel portion, and each said striking element when in its lowermost position having its toe portion inclined upwardly and outwardly and the innermost part of its heel portion lying substantially in the same plane as the innermost part of the heel portion of the next striking element as the latter reaches its lowermost position.

55 2. A machine for harvesting beets and like tubers according to claim 1 wherein two rotatable members are provided, the striking elements of each set being supported in a circular arrangement on one of said members,

each of said members being secured to a separate drive shaft and the axes of the said shafts enclosing an angle of at least 140° and not exceeding 160° whose sides converge upwardly.

3. A machine for harvesting beets and like tubers according to claim 2 wherein said shafts are inclined inwardly, upwardly and forwardly of the machine so that a plane containing the axes of both shafts encloses with a horizontal plane an angle less than 90°.

4. A machine for harvesting beets and like tubers according to claim 3 wherein a grate is provided between

the sets of striking elements and a conveyor for receiving the beets.
